UNITED STATES PATENT OFFICE.

JAMES T. HAMBAY, OF NEW YORK, N. Y.

DETECTOR-BAR.

No. 838,709.

Specification of Letters Patent.

Patented Dec. 18, 1906.

Application filed March 28, 1906. Serial No. 308,395.

To all whom it may concern:

Be it known that I, JAMES T. HAMBAY, a citizen of the United States, and a resident of the city of New York, in the State of New York, have invented certain new and useful Improvements in Detector-Bars, of which the following is a specification.

My invention relates to improvements in detector-bars, and has particular reference to detector-bar brackets, the object of the invention being to produce a device which will be more compact and easy of construction and operation than heretofore.

In the following I have described with reference to the accompanying drawings one form of device illustrating the application of my invention, the features thereof being hereinafter more particularly pointed out in the claims.

20 In the drawings, Figure 1 is a side elevation of one embodiment of my invention. Fig. 2 is a sectional view of the structure shown in Fig. 1 along the line 2 2 thereof. Fig. 3 is a sectional view of the structure shown in Fig. 1 along the line 3 3 thereof; and Fig. 4 is a detail view of the device, parts being broken away to illustrate the construction thereof more clearly.

Similar letters of reference indicate similar parts throughout the several views.

a indicates the ordinary T-rail to which the device is adapted to be applied.

b indicates the bracket adapted to support the operating parts. The bracket b comprises in part a portion c, adapted to fit into the side of the rail, and is provided with an opening d to accommodate a bolt for clamping the bracket to the rail. At the lower portion of the bracket b are provided lugs or extensions e e, adapted to fit over the base of the rail and to hold the bracket in proper alignment therewith. An enlarged journal-bearing f is also provided at said lower portion of bracket b and is preferably cast integrally therewith. A crank-arm h is mounted on said bearing f so as to freely oscillate thereon, the comparatively large bearing-surface of bearing f forming a very firm support for the crank-arm. The upper end of the crank-arm h is adapted to be connected with the detector-bar i by means of a suitable pivot j. An oil-hole k, protected by projecting flange l, may also be provided for lubricating the pivot j. The crank-arm h is preferably so mounted on the bearing f that the bearing projects slightly above the crank-

arm so as to form an offset or shoulder m. A back plate n is adapted to fit over the bearing f and to be seated on said shoulder m. Plate n is fastened to the bracket b by means 60 of a bolt o passing through said plate and bracket at a point preferably eccentric to the axis of oscillation of the crank h, the object being to so hold the parts together that the back plate n, when fastened in place, will be 65 held against movement. This object is further accomplished by the comparatively large area of the bearing f, against which the plate n rests. A further object for passing bolt o eccentrically through said bearing and 70 plate is to advance the fulcrum-point of the crank-arm against outward thrust as near to the operating end of the crank-arm as possible, thus decreasing the strain on the bolt and increasing the ability of plate n to resist 75 the outward thrust of the crank-arm. An oil-hole p, protected by a projecting flange r, may be provided for the purpose of lubricating the bearing f.

The operation of the device will be readily 80 understood from the foregoing, the bracket b and bearing f forming a firm support and bearing for the crank h, adapted to actuate the detector-bar i in the usual manner.

It is obvious that the details of construction as shown and described may be considerably varied without departing from the spirit of my invention, and I do not restrict myself to the details as shown and described.

What I claim, and desire to secure by Letters Patent of the United States, is—

1. An apparatus of the character described including a bracket, a bearing integral therewith, a crank-arm supported directly on said bearing and means for holding the crank-arm 90 against outward thrust.

2. An apparatus of the character described including a bracket, a bearing integral therewith, a crank-arm supported directly on said bearing and a plate adapted to be secured to 100 said bearing and to hold the crank-arm against outward thrust.

3. An apparatus of the character described including a bracket, a bearing integral therewith, a crank-arm supported directly on said bearing, a plate adapted to hold the crank-arm against outward thrust and a bolt adapted 115 to secure said plate to said bearing.

4. An apparatus of the character described including a bracket, a bearing thereon, a crank-arm supported on said bearing, a plate adapted to hold the crank-arm against out-

ward thrust and a bolt for securing said plate to said bearing said bolt passing through said bearing eccentrically to the axis of oscillation of the crank-arm thereon.

5. An apparatus of the character described including a bracket, a bearing integral therewith having a relatively large bearing-surface and a crank-arm adapted to be supported directly on said bearing so as to oscillate thereon.

10. An apparatus of the character described including a bracket, a bearing integral therewith, a crank-arm supported directly on said bearing, means for holding said crank-arm against outward thrust and means for holding said bracket in alinement with the rail.

15. An apparatus of the character described including a bracket, a bearing integral therewith, a crank-arm supported directly on said bearing, a plate adapted to be secured to the face of the bearing and to hold the crank-arm against outward thrust.

20. An apparatus of the character described

including a bracket, a bearing integral therewith, a crank-arm supported directly on said bearing in such manner that said bearing projects through said crank-arm to form a shoulder and a plate adapted to be secured on said shoulder to hold said crank-arm against outward thrust.

25. An apparatus of the character described including a bracket, a bearing integral therewith, a crank-arm supported directly on said bearing in such manner that said bearing projects through said crank-arm to form a shoulder, a plate adapted to be secured to said bearing to hold the crank-arm against outward thrust and a recess in said plate adapted to fit over said shoulder.

30. In witness whereof I have hereunto signed my name in the presence of two subscribing witnesses.

JAMES T. HAMBAY.
